UNITED STATES PATENT OFFICE.

FRANK H. HARRIMAN, OF SOUTH GLASTONBURY, CONNECTICUT, ASSIGNOR OF ONE-HALF TO THOMAS H. SMITH, OF FORT HILL, CHESTER, CONNECTICUT.

FUEL-ECONOMIZER.

1,334,952.

Specification of Letters Patent. Patented Mar. 30, 1920.

Application filed March 17, 1919. Serial No. 283,088.

To all whom it may concern:

Be it known that I, FRANK H. HARRIMAN, a citizen of the United States, and a resident of South Glastonbury, in the county of 5 Hartford and State of Connecticut, have invented certain new and useful Improvements in Fuel-Economizers, of which the following is a full, clear, and exact description, whereby any one skilled in the art may 10 make and use the same.

The invention, as indicated by its title, relates to an apparatus for effecting an economy in fuel consumption in gas engines and incidentally to the reduction of carbon 15 deposits in the cylinders of such an engine.

Economy in fuel is effected by the well known means of supplying a vapor, in conjunction with the gas mixture, to give a more complete combustion to the vaporized 20 gas. The benefits incidentally attained accrue from decreasing the carbon deposit and automatically providing for the consumption and removal of carbon through the use of the more perfect mixture which is attained by the steam introduced with the 25 mixture.

The object of the invention is to provide a simple device which will be automatically controlled by the heat developed from 30 operation of the engine and will in no way affect the normal operation of the engine and its appurtenant parts when it is desired to start the engine.

In other words, the engine will operate 35 without reference to the fuel economizer, under the normal and prescribed gas mixture, until sufficient heat is developed to insure introducing to the mixture the requisite quantity of steam to produce the desired results. There is no liability of introducing an excess of moisture in the form of 40 water which will deaden the mixture and prevent easy starting of the engine.

Referring to the drawings:

45 Figure 1 is an illustrative view showing the application of the device.

Fig. 2 is a sectional view through the generator and appurtenant parts.

Fig. 3 is a horizontal section through the 50 casing.

Fig. 4 is a detail cross-sectional view on the line 4—4 of Fig. 2.

It is not at all new in the art to provide 55 water or steam in conjunction with the carbureted mixture of fuel oil to enhance the

value of the mixture and reduce its tendency to produce a residual carbon scale in the head and about the valves of an engine. In such devices, so far as known to applicant, provision has not been made for "flashing" 60 water into steam and controlling this operation by the heat conditions developed by the engine.

The invention herein disclosed overcomes the objections heretofore encountered, 65 wherein water might be drawn into the mixture to give too high a saturation for proper operation, and where there is liability of producing an over-saturated condition of moisture when starting the engine. 70

Briefly, these difficulties are overcome by utilizing a flash chamber in conjunction with a vacuum chamber, vacuum in which is induced by the suction of the engine at the inlet manifold, and controlling the suction chamber by a thermostatically controlled vent, so that the vacuum of the inlet manifold will be ineffective on the vacuum chamber of the flash generator until a predetermined temperature condition has been 75 attained in the steam generator.

My device differs widely in mode of operation and results from devices heretofore known to me, even those employing a thermostatic control for regulating the flow of 85 water to a steam-producing chamber. In my device, the water supply is located below the level of the vacuum chamber and the vacuum chamber itself is controlled by a thermostat and valve, so that there is no 90 possible liability of water flooding into the steam generator. By arranging the thermostat to control an air valve and vent in my vacuum chamber, I avoid placing reliance upon valves for shutting off or controlling the flow of water, thus making the device most dependable. The suction in my vacuum chamber raises the water from a low level and causes it to drop through a restricted water tube into the flash generator, 95 so long as the thermostat re-acts to keep the vacuum chamber closed against ingress of air. The moment the thermostat opens the air vent, the flow of water to the apparatus ceases. It will be obvious that I thus avoid 100 placing reliance upon more or less delicate valves subject to leakage for controlling the flow of water, my whole apparatus being dependent upon the degree of suction—a much 105 more delicate, though certain, means of con-

110

tral. It further permits locating the water tank supply below the level of the vacuum chamber, thereby obviating all liability of flooding.

5 Referring to the drawings, the numeral 1, denotes an engine provided with the usual

appurtenances in the way of carbureter, etc., and, as illustrated, has an inlet manifold 2, communicating with the carbureter and the

10 combustion chamber of the engine, and an exhaust manifold 3, through which the exhaust gases pass. The interior mechanism of the engine is not shown as it may be of any well known type of construction.

15 A supply tank W, containing a sufficient quantity of water, is located preferably at a level below that of the carbureter C, and is connected through a pipe line 4, with the economizer E.

20 The economizer is of simple construction and comprises in the main a flash generating chamber 5, which is in the form of a nipple having a nut 6, and an exterior thread 7, so that it may be inserted through an 25 opening in the exhaust manifold 3, of the engine.

The generator nipple 5, has an interior thread into which is screwed a tubular casing 8, which provides, in conjunction with 30 the chamber of the nipple 5, a vacuum chamber 9.

A nipple 10, at one side of the tubular casing 8, provides means for the attachment of a pipe line 11, which extends to the intake 35 manifold 2.

The upper end of the tube 8, is closed by a threaded nipple 12, which nipple supports a delivery tube 13, and has means for the connection of the water pipe line 4.

40 A passage 14, extends through the nipple 12, from the tube 13, to the pipe line connection 4, so that water passing through the pipe line will draw through the tube 13.

The tube 13, has a contracted nozzle 15, at 45 its lower end so that the water is delivered to the flash chamber in comparatively small quantities, drop by drop.

The passage 14, communicates with an air vent 16, which vent is controlled by a valve 50 17.

The purpose of the air vent 16, and valve 17, is to either make the suction of the manifold effective for producing a partial vacuum in the vacuum chamber 9, or to break the vacuum by introducing air 55 through the pipe line and nozzle 4.

The valve 17, is preferably mounted upon a lever 18, pivoted as at 19, and with its outer end connecting through a pivoted link 20, with a thermostatic bar 21. The thermostatic bar 21, is secured to the outer side 60 of the exhaust manifold 3, in any suitable manner, as by screws 22, and intermediate spacer blocks 23.

It will be quite apparent from the above 65 description that with the air vent 16, open,

the suction induced in the intake manifold of the engine will not be effective for producing the requisite vacuum in the chamber 9, to draw up water from the tank W, through the pipe connection 4, and tube 13, 70 to the flash chamber 5.

Just as soon as the engine has been started and the manifold has become sufficiently heated, the thermostat 10, will re-act, closing the valve 17, and thereby the air vent 16, 75 whereupon the suction of the intake manifold will produce a partial vacuum in the chamber 9, and one sufficient to draw water from the tank W, into the flash nipple or generator 5.

80 With the nipple 5, now highly heated, drops of water passing through the tube 9, will be flashed into steam which will be drawn over by the suction of the intake manifold into said manifold, above the carbureter. Thus, it will be intimately mixed with the gaseous mixture of air and liquid fuel passing to the engine cylinders. This condition will maintain so long as the engine is in operation and sufficient heat is 85 developed in the exhaust manifold and flash nipple 5, to produce the requisite steam.

When the engine is stopped and cooled down, the thermostat bar 21, through its connections, will open the valve 17, thus 90 venting the system, so that the suction of the intake manifold will not create a sufficient vacuum in the chamber 9, to draw over water from the tank W.

95 In other words, the steam generation is 100 made dependent upon the proper heat conditions of the engine and is inoperative at the moment of starting the engine, thus overcoming the objections heretofore encountered in devices of this character, which 105 result from drawing moisture into the mixture before the engine is sufficiently heated to utilize it properly. Starting the engine with this system is just as easy as though it were not applied, and after the engine 110 is in operation the steam generation is automatically controlled.

What I claim as my invention and desire to secure by Letters Patent is:

115 1. A fuel economizer comprising a flash generator heated by the products of combustion of the engine and having a vacuum chamber, said vacuum chamber communicating with the intake manifold of the engine and with a source of water supply, 120 said water supply being located below the vacuum chamber and the water being raised to the chamber by the suction of the vacuum chamber, means for breaking the vacuum in said vacuum chamber, and a thermostat for controlling said means.

125 2. An economizer for gas engines comprising a vacuum chamber communicating with a flash generator and having communication with the inlet manifold of the en- 130

gine and deriving its heat from the exhaust manifold of the engine, a connection from said vacuum chamber to a source of water supply located below the inlet manifold, 5 the water of said supply being fed to the vacuum chamber only when suction is induced therein, and automatic means controlled by a thermostat for breaking the vacuum of the vacuum chamber.

10 3. A fuel economizer comprising a flash generator heated by the products of combustion of the engine and having a vacuum chamber, a connection from the vacuum chamber to the intake manifold of the engine, whereby a sub-atmospheric pressure 15 will be maintained in the vacuum chamber when said chamber is closed to atmospheric pressure, a constantly open connection from the vacuum chamber to a source of water supply, said supply located at a lower level 20 than the economizer, and thermostatically controlled means for breaking the vacuum in said vacuum chamber.

4. In a device of the character described, 25 a generator nipple adapted to be applied to the exhaust manifold of the engine, a casing member engaging said nipple and forming therewith a chamber, a dependent tube projecting through said chamber into the 30 generator nipple, a connection from said tube to a source of water supply, a connection from said chamber to a suction inducing apparatus such as the intake manifold

of an engine, an atmospheric air vent communicating with the aforesaid chamber and 35 adapted when open to the passage of air to neutralize the sub-atmospheric pressures induced in the chamber, and means automatically controlled by the heat generated by the operation of the engine for closing said air 40 vent.

5. In a device of the character described, a nipple adapted for insertion in the exhaust manifold of an engine, a casing extending from said nipple, a threaded plug 45 engaging the upper end of said casing and closing the same except for a communication therethrough to a source of water supply located below the level of the casing, and a communication therethrough to the 50 atmosphere, a connection from the chamber to the intake manifold of the engine, and an automatically controlled valve actuated by a thermostat for opening and closing the atmospheric communication, 55 whereby the chamber of the casing will be subjected to sub-atmospheric pressures for drawing water into the chamber from the low level water supply or to atmospheric pressures for neutralizing the suction of the 60 chamber.

FRANK H. HARRIMAN.
